US00D977355S

(12) **United States Design Patent** (10) **Patent No.:** **US D977,355 S**
(45) **Date of Patent:** **** Feb. 7, 2023**

(54) **TEMPORARY FLEXIBLE PAVEMENT MARKER**

(71) Applicant: **TrafCo Industries, Inc.**, Eagle Lake, TX (US)

(72) Inventors: **Lesley M. Carey**, Eagle Lake, TX (US); **Lonny E. Daley**, Eagle Lake, TX (US)

(73) Assignee: **Trafco Industries, Inc.**, Eagle Lake, TX (US)

(**) Term: **15 Years**

(21) Appl. No.: **29/698,174**

(22) Filed: **Jul. 15, 2019**

(57) **CLAIM**

The ornamental design for a temporary flexible pavement marker, as shown and described.

DESCRIPTION

FIG. 1 is a front perspective view of the first embodiment of a temporary flexible pavement marker, showing our new design.

FIG. 2 is a front elevational view of FIG. 1.

FIG. 3 is a rear elevational view of FIG. 1.

FIG. 4 is a right side view of FIG. 1.

FIG. 5 is a left side view of FIG. 1.

FIG. 6 is a top plan view of FIG. 1.

FIG. 7 is a bottom plan view of FIG. 1.

FIG. 8 is a front perspective view of the second embodiment of a temporary flexible pavement marker, showing our new design.

FIG. 9 is a front elevational view of FIG. 8.

FIG. 10 is a rear elevational view of FIG. 8.

FIG. 11 is a right side view of FIG. 8.

FIG. 12 is a left side view of FIG. 8.

FIG. 13 is a top plan view of FIG. 8; and,

FIG. 14 is a bottom plan view of FIG. 8.

The broken lines in the drawing illustrate portions of a temporary flexible pavement marker that form no part of the claimed design.
